CRUTCH FOR SURGICAL TABLES

Harold J. Lawrence, Mariemont, Ohio, assignor to
The Liebel-Flarsheim Company, Cincinnati,
Ohio, a corporation of Ohio

Application November 5, 1941, Serial No. 417,931

4 Claims. (Cl. 311—11)

This invention relates to improvements in operating and surgical tables of the type employed to support a patient undergoing an operation or diagnosis and, while the invention may be applied to operating tables for varying purposes, it has been devised particularly for use in conjunction with tables used for genitourinary operations and examinations, and in the specification which follows the use of the apparatus is illustrated in this environment.

In the use of tables of this type the patient lies on his back, with legs spread and supported in so-called crutches located usually adjacent the knee joints. The present invention is directed particularly to improvements in the crutch or support apparatus.

It is requisite that the crutches be adjusted so as to accommodate patients of varying size and also to accommodate varying operative or diagnostic positions. It is frequently the case that the limbs need be spread apart so much that the patient becomes very uncomfortable.

The principal objective of the present invention has been to provide adjustable crutch apparatus so arranged as to support the legs in a relaxed position during the preoperative period but adapted to be swung or "inched" apart to the operative or diagnostic position at the proper time. By the present improvement the patient remains in the least comfortable position during the shortest possible time, that is, only during the operation or examination, and at other times, for example, while awaiting the doctor, the patient is comfortably supported.

A further object is to provide crutches or supports which may be raised or lowered readily to any desired height and also to provide means upon the crutches or supports whereby they may be moved inwardly or outwardly to fit the knee joints in the most comfortable position.

A further object of the invention has been to provide a structure in which the crutches for supporting the patient's legs at the knee portions are swung within a yoke or cradle in such manner that the patient's limbs are suspended in the most comfortable position even when the legs are spread.

It is also the purpose to provide separate locks for the various adjustable members. In the past all adjustments have been controlled from a single lock and it has been very difficult to locate all parts in their desired prearranged positions and have them remain so during the period that the lock is being fastened. In fact, the difficulty has been such that it is usually conventional practice

for the attendant to arrange the patient and make the adjustments while the doctor is preparing for the operation or the diagnosis, despite the fact that the patient thereafter frequently must remain in the most uncomfortable position a relatively long period of time awaiting the doctor's preparations. Minor alterations cannot conveniently be made after an operation is begun.

Briefly, in the preferred structures of the present invention, the crutch or supports in which the patient's knees are rested are carried by bracket members which may be attached either to the side rails of the table or to the side and end rails, as by corner pieces, one crutch for each leg. Posts are slidably supported from the brackets, the connections preferably being through leave clamp locks so arranged that the edges of the leaves tend to bite into the surface of the post to withhold it against downward movement. A lever extending forwardly from the bracket is arranged to lift the leaves to permit the posts to be lowered.

At its upper end each post rotatably carries a hub to which the main support arm of the crutch is fastened. The rotatable hubs of the posts, however, cooperate with stationary hubs fixed firmly to the posts, the meeting faces constituting a ratchet permitting movement of the arms only in an outward direction. The ratchets are unlocked by separating the hubs thereby permitting the arms to be swung inwardly. During the preoperative period the arms are in the inward position, extending endwise from the table so that the patient's legs supported in the crutches are in relaxed position, straight out. By pushing outwardly upon each arm the crutch, and thus the patient's leg, is carried with it and prevented from returning inwardly by the ratchet apparatus.

The crutch elements are U-shaped elements adapted to fit the underneath part of the knee joints or calves of the legs, the forward and rearward portions of the crutches being appropriately splayed to avoid cutting the flesh. The crutches, in turn, are pivotally carried in cradles which extend upwardly from the arms and are slidable thereon as well as rotatable about axes extending laterally of the arms. In the preferred structure the crutches are suspended in the yokes or cradles on an axis above the center of gravity and, therefore, the crutches constitute movable suspension units for the patient's legs. By virtue of this arrangement the patient is permitted some latitude in flexing the knees and in permitting the feet to hang in the most comfortable position, and the

crutches being movable conform with the leg contours to provide support therefor substantially regardless of the limb positions. Thus it will be seen that the apparatus is completely adjustable yet the major adjustments, spreading of the crutches and lowering of the legs, may be performed by the doctor or attendant prior to or during the operation or diagnosis so that the patient is enabled to remain in the most comfortable position until such time.

Other features and advantages are shown in the drawings in which a preferred embodiment of the present invention is disclosed.

Figure 1 is a perspective view showing a genitourinary table equipped with typical crutch support apparatus of the present invention.

Figure 2 is a side elevation of a crutch unit.

Figure 3 is a cross sectional view taken on the line 3—3 of Figure 2.

Figure 4 is a fragmentary sectional view taken on the line 4—4 of Figure 2.

Figure 5 is a fragmentary elevation taken along the line 5—5 of Figure 2.

Figure 6 is a cross sectional view taken on the line 6—6 of Figure 2.

Figure 7 is a cross section taken on the line 7—7 of Figure 6.

Figures 8 and 9 are diagrammatic views illustrating the operation of the leaved lock shown in Figures 6 and 7.

The table shown in Figure 1 is comprised of a chassis indicated generally at 2 and a table member 3 which is pivotally mounted to the chassis through the journals 4. Elevating apparatus designated 5 is provided for tilting the table to various angular positions. For diagnostic purposes and for use in X-ray photography the table is sometimes equipped at its forward edge with a bucky diaphragm which is adapted to receive an X-ray film in a cassette. Also, in some instances, gentitourinary tables are provided with an arm extending upwardly from one side thereof to carry an X-ray tube over the cassette. The details of the table proper form no part of the present invention and are therefore not described in detail in the specification.

The knee crutch units, indicated generally at 7, to which the present invention particularly is addressed, are located at the forward end of the table at opposite sides thereof, one crutch for each leg, each unit being carried by a bracket 9 which is bolted to the table frame as at 10. Brackets 9 may be corner brackets, as shown, or may be fastened to the end or side walls of the table frame, as the case may be. Corner brackets may be fastened directly to most tables now in use and it is to be noted therefore that the crutch units of the invention may be manufactured as table accessories or may be built permanently into the table structure.

Each corner bracket 9 carries a housing or clamp block 11 having a passageway extending vertically therethrough for the reception of a post 12. The post preferably is of square or rectangular configuration or so arranged as to present a relatively flat clamping surface 13 which is adapted to be engaged by clamp leaves 14 residing angularly with respect thereto. The clamp leaves fit within a cavity 15 extending part way across the clamp block, terminating at the forward edge thereof in a lever recess 16. Each of the clamp leaves contains an aperture conforming approximately to the external configuration of the post 12 whereby the post may be slid through the

leaves after they have been nested and fitted within the passageway 15.

Additional bores 17 are provided in the leaves at the rearward side of the post 12 to receive a presser pin 18. The pin 18 resides in a bore 19 of the clamp block with a compression spring 20 interposed between the top of the pin and a set screw 21 which is threaded into the clamp block. The bore, 19, is carried through the block into a recess below the passageway 15 to provide clearance for the lower portion of the pin. At the opposite side of the post 12, the upper leaf of the series 14 is configurated to provide a foot portion 22 and a compression spring 23 is confined within a cavity 24 to press downwardly upon the foot.

The springs 20 and 23 press upon the pile of leaves at opposite sides of the post to seat the leaves on an arm 25 of a lever 26. Handle portion 27 of the lever extends outwardly beyond the clamp housing and is bent downwardly so that the knee portion of the lever constitutes a fulcrum cooperating with the terminal edge of the passageway 16 whereby the rearward extremity of the lever arm 25 is elevated when the handle 27 is depressed. The arm 25, like the leaves, is provided with clearance openings for the post 12 and the pin 18, and a boss 28 is struck from the face of the lever arm to reduce the friction incidental to the movement of the arm.

In the preferred structure the clamp block is a two-piece member, the main passageway for the post 12 being located in one section and the other constituting a cover plate 29 attached thereto by means of screws 30 for holding all the parts in assembled relationship.

It will be seen from Figures 7, 8 and 9 that the openings in the clamp leaves and the angular relationship of the leaves with respect to the axis of the post are such that the edges of the leaves 40 tend to bite into the face 13 (and the opposite face of the post if desirable). By operating the lever 27 the angularity of the leaves is so decreased that they reside more nearly perpendicular to the post. This movement has the effect of 45 increasing the width of the openings and causing the edges of the leaves to be moved out of engagement with the clamping edge 13 of the post 12. When this is done the post readily may 50 be lowered. By releasing lever 27 the leaves drop back into the more inclined position and again clamp the post with respect to the clamp block.

While other locks may be used in conjunction with the present apparatus the post clamp unit shown in the drawings is preferred because it provides positive locking in a simple and expedient manner. In certain operative or diagnostic positions considerable weight is thrown on the post and it is necessary that the lock be arranged to hold the post firmly and positively against downward movement lest an accident happen during an operation. It is also to be noted that if the post is to be lowered the doctor or attendant may press downwardly upon the lever 27 with the elbow to make the adjustment.

At the upper part of each post the "inching" adjustment apparatus for the crutches is located. A preferred embodiment of this feature of the invention is as follows:

A hub 31 is pinned to the post in a position adjacent its upper end by means of pin 32. Guide pins 33 extend upwardly from the hub into bores 34 located in spaced positions annularly in the face of a slideable and non-rotatable ratchet member 35, the latter being journaled on a counter-turned portion 36 of the post 12. The ratchet

member 35 is held against rotation about the post by pins 33 but is slideable longitudinally of the post upon the journal portion 36 thereof.

Hub 31 is counterbored as at 37 and a compression spring 38 is seated within the counterbore around the journal portion of the post, the upper end of the spring being in abutment with the lower face of the slideable ratchet member.

The post is also counterturned as at 39 to carry a rotatable ratchet member 40 so located that its lower face rests against a shoulder 41. The upper end of this element has a recess in it for seating a washer 42 through which a screw 43 passes into threaded engagement with the counterturned portion 39 of the post. The washer 42 rests upon the end of the shaft portion 39 and the clearances are such that when the bolt is tightened the ratchet member 40 may rotate freely around shaft 39.

The meeting faces of elements 35 and 40 are configurated to constitute a ratchet, the teeth 44 being cut therein over a portion of the meeting faces, the balance being counterbored to provide clearance as at 45. Ratchet member 40 is rotatable with respect to the post but not movable longitudinally thereof while the ratchet element 35 is not rotatable with respect to the post but is movable longitudinally thereof. The spring 38 urges the non-rotatable element 35 upwardly against the ratchet member 40.

Rubber bumpers are slipped over the posts and against the lower face of the hub 31 so as to act as shock absorbers in the event that the post is permitted to drop freely under a heavy load.

Support arms 46 extend rigidly from each rotatable ratchet element 40 and the teeth of the ratchet elements of each set are arranged as to slide over one another when the supporting arms 46 are swung in a direction outwardly from the table and to lock with one another to prevent the arms from swinging inwardly.

The crutches in which the patient's knees are supported are pivotally swung in cradles, the cradles, in turn, are rotatably carried on saddle blocks, and the saddle blocks are slideable longitudinally of the support arms 46 to obtain latitude in the adjustability of the apparatus. In the preferred structure the saddle blocks, designated 47, have apertures therein for receiving the support arms 46 and clamp screws 48 are provided on the saddle blocks whereby the blocks may be fastened rigidly to the arms once they have been moved to the desired position. The upper face of each saddle block constitutes a journal 49 for seating the lower face of a central boss 50 which has arms 51 extending outwardly and upwardly therefrom in spaced relationship to constitute a cradle crutch. A sleeve 52 is located in a bore within the boss 50 and a bolt 53 is passed through the sleeve and into threaded engagement with the saddle block for assembly of the cradle with the saddle block.

It is to be noted that the crutches are suspended in the cradles, the center of gravity of each crutch being somewhat below its pivotal axis. The lower limbs of a patient lying on a table hang down from the forward edges of the crutches while the thighs rest on the rearward portion. It is to be seen, therefore, that the crutches naturally tend to assume the position in which they offer the utmost support for the patient's limbs and, yet being swung within the cradles, permit the patient's lower limbs to move about somewhat freely.

Metal washers 54—54 carrying a rubber washer

55 therebetween are located beneath the head of the bolt 53 and rest on a seat provided at the upper end of sleeve 52. The rubber washer is of sufficient diameter to extend beyond the periphery of the washers 54 and also beyond the periphery of the boss 50 so that its outer edge constitutes a bumper against which the underneath portions of the crutch may come into contact without damaging the crutch.

Each crutch 56 is a trough-like unit having a portion inclined downwardly at opposite sides so that it is adapted to support the knee portion of a patient when the legs are bent.

To pivotally carry the crutch the cradle arms are bored to receive stud bolts 57. These pass through appropriate sleeves 58 in the cradle and constitute journals for the stud bolts, with the terminal edges of the sleeves extending inwardly beyond the faces of the cradle arms so as to provide clearance for the crutch.

At the opposite outer faces of the crutch reinforcing members 59 are riveted thereto. The studs are threaded through the reinforcing members and the crutch walls.

It is preferred that the axis of rotation of the cradles be inclined outwardly upwardly with respect to the table so that the crutches are positioned to conform more nearly to the position of the legs when the legs are in the spread position.

It will be seen that the crutches are free to move with respect to the cradle and the cradles in turn are free to move pivotally about the saddle blocks so that the parts may be adjusted to support the legs comfortably regardless of the position in

35 which the patient may reside. The slideable adjustment of the saddle blocks along the arms enables patients of various size to be accommodated. In the normal operation of the device the patient may reside on the table with legs straight out in the relaxed and most comfortable position, with the knees supported in the crutches. When preparations have been made the doctor may simply nudge each arm outwardly, for example, by pushing upon it with his shoulder or elbow.

45 The ratchets act to prevent inward movement of the arms under the pressure inserted upon them by the patient's legs. When the operation or diagnosis is completed the attendant simply presses downwardly upon the slideable ratchet elements 35 withdrawing the teeth thereof from engagement with the teeth of the rotatable element 40, thereby permitting the support arms to be retracted to permit the patient's legs to move to retracted position.

55 The invention has been disclosed particularly in relation to its use upon a genitourinary table, but the invention is not limited to this particular usage and may be employed for other diagnostic or operative purposes. Claims directed particularly to the pivotal suspension of the crutch supports are disclosed and claimed in a copending application Serial No. 476,100 which is a division hereof.

Having described my invention, I claim:

1. An accessory for a table comprising crutch support apparatus including a bracket adapted to be attached to the table, a post extending upwardly from the bracket, an arm rotatably supported by the post and extending laterally therefrom, and ratchet means constituted by a non-rotatable member slidably carried by said post and a non-slidable member rotatably carried by said post, said members having cooperating ratchet teeth normally permitting the arm to be swung in the one direction of rotation thereof

and preventing the arm from being rotated or swung in the opposite direction.

2. An accessory for a table comprising crutch support apparatus including a bracket adapted to be attached to the table, a post extending upwardly from the bracket, an arm rotatably supported by the post and extending laterally therefrom, ratchet means constituted by a non-rotatable member slidably carried by said post and a non-slidable member rotatably carried by said post, said members having cooperating ratchet teeth normally permitting the arm to be swung in the one direction of rotation thereof and preventing the arm from being rotated or swung in the opposite direction, and means for separating said members so that the arm may be swung in either direction.

3. A crutch support apparatus adapted for use in conjunction with an operating table comprising a bracket, a post, a hub attached to the post at one end thereof, a ratchet member rotatably journalled on the post and held against movement longitudinally thereof, a second member arranged to be moved longitudinally of the post and held against rotation with respect thereto, the said ratchet members having their meeting faces constituting a ratchet, an arm carried by the rotatable ratchet member and means for normally holding the meeting faces of the members

in engagement, whereby the arm may be swung in one direction of rotation but is prevented by the ratchet member from being swung in an opposite direction of rotation, the said post at its opposite end being adapted to be attached to the genitourinary table so as to be supported therefrom.

4. An apparatus adapted for use in conjunction with an operating table comprising a post, a member fixed to the post adjacent one end thereof, a first ratchet member journalled on the post adjacent the fixed member, means interconnecting the fixed member and the first ratchet member to permit the first ratchet member to be moved longitudinally of the post but not rotated with respect thereto, a second ratchet member rotatably journalled on the post adjacent the first, the said ratchet members having cooperating ratchet teeth thereon, spring means for urging one of the ratchet members toward the other for engagement of the teeth thereof, an arm carried by the second ratchet member so as to extend laterally of said post and a crutch support carried by said arm, the said post being adapted to be attached to a genitourinary table for support thereof, and the said ratchet members permitting the arm carried by the post to be swung in one direction and locking the arm against rotation in an opposite direction.

HAROLD J. LAWRENCE.
